UNITED STATES PATENT OFFICE.

EMIL ALBERT DRECHSEL, OF GORNSDORF, GERMANY, ASSIGNOR TO THE FIRM OF
ALBIN DRECHSEL SOHNE, OF GORNSDORF, GERMANY.

FRAMEWORK KNITTED FABRIC.

1,375,575.

Specification of Letters Patent. Patented Apr. 19, 1921.

Application filed September 22, 1916. Serial No. 121,663.

To all whom it may concern:

Be it known that I, EMIL ALBERT DRECHSEL, a citizen of Germany, residing at Gornsdorf, Saxony, in the German Empire, have 5 invented certain new and useful Improvements in Framework Knitted Fabrics, of which the following is a specification.

My invention relates to frame work knitted fabrics, and in particular to fancy fabrics; its object being to provide a fancy fabric of this kind which though having a 10 design worked into it retains its closeness and furthermore allows of innumerable designs to be produced thereon. I achieve 15 this object by placing the loops selected for the design diagonally relatively to the direction of the normal loops and across the adjacent loops of normal position. By the latter feature the loops forming the design 20 are slightly raised out of the face of the fabric, whereby a good prominence of the design is obtained in conjunction with the feature that the loops used for the formation of the design digress from the direction of 25 the loops of normal position.

It is a further object of my invention to provide a method for producing frame work knitted fancy fabrics of the character and features hereinbefore described.

With these objects in view, I have illustrated some practical embodiments of my invention by way of example, in the accompanying drawings which form a part of the specification.

Figures 1 to 3 illustrate, in a diagrammatical manner, the formation of the design; while in Figs. 4 to 7 some of the designs are shown which can be produced by my invention.

Referring to the drawings, Fig. 1 illustrates an ordinary plain course of loops *a*, *b*, *c*, *d*, *e*, *f*, *g*, *h*, *i*, *k*; it being assumed that the loops designated *c*, *d*, and *g*, *h*, are selected for the formation of a certain design. The numerals 1, 2, 3, 4, 5, 6, 7, 8, 9, 10, 11 designate needle hooks of a straight bar knitting frame. The loops *a*, *b*, *c*, *d*, *e*, *f*, *g*, *h*, *i*, *k*, hang upon the needle hooks 1, 2, 3, 4, 5, 6, 7, 8, 9, 10. In proceeding to produce the designs, the loops attached to the needle hooks 1 to 10 are divided into three groups; one group, comprising the loops *d* and *h*, being allotted to the formation of the design, a further group, comprising the loops *c* and *g* and being situated either on

the right or on the left of the loops of the first group, are selected to be transferred to cross the loops of the first group, while the third group comprises the remaining loops *a*, *b*, *e*, *f*, *i*, *k*. In producing the design, the 60 loops of both of the groups last named are synchronously detached from their respective needle-hooks and shifted in the same direction, but for varying amounts, so much so that after the transference the loops *c* and *g* will extend over and, hence, cross the loops *d* and *h* which have not been taken off their respective needle-hooks. The crossing obtains on the rear of the fabric; see Fig. 2. The remaining loops *a*, *b*, *e*, *f*, *i*, *k* have only 70 been shifted sufficiently to provide for the needle-hooks 5 and 9 to become free to receive the loops *c* and *g*; while the needle-hooks 2, 3 and 6, 7, and 10, 11, which also became temporarily empty, are now charged 75 again so that no gaps are produced, as will be apparent from Fig. 3. It follows that for the production of this example of a design, the loops *c* and *g* contributing to the formation of the design, are shifted for the space 80 of two needle divisions, while the remaining loops *a*, *b*, *e*, *f*, *i*, and *k* are shifted but one needle division, in order to obtain an uninterrupted course of loops occupying, as initially, an unbroken series of needle- 85 hooks; the consecutive order of the loops being the same again, except for the loops crossing each other which have exchanged their places. In Fig. 2 the shifted loops are shown in an oblique position in order to 90 more clearly illustrate the steps of the method employed, Fig. 3 reproducing the proper position of the course, for the shift to which a part of the loops is subjected extends to the entire fabric. After the performance of the shift the columns of loops 95 are again disposed vertically as initially, compare Figs. 1 and 3; with the exception of the loops contributing to the formation of the design which loops now cross each 100 other symmetrically.

In consequence of the fact that the loops forming the design digress from the position of the normal loops, and because of the superposition of loops within the dominion of the design, the latter is raised out of the face of the fabric and is thereby rendered prominent.

Quite a large variety of designs may be produced by this invention, by altering the 110

relative position of adjacent loop crossings, both within the same course of loops and between superposed courses. Some such simple designs are reproduced in Figs. 4 to 6. In Fig. 4 two adjacent loop crossings are placed side by side and the loop crossings of superposed courses form vertical columns, while in the design reproduced in Fig. 5 two adjoining loop crossings of superposed courses form oblique columns. In Fig. 6 a design is shown, in which single loop crossings of superposed courses form zig-zag paths; while in Fig. 8 another variety is shown in which the number of loop crossings changes from course to course. In the same manner the adjacent loop crossings of superposed courses may be composed to form figures of any shape and contents.

For carrying my present invention into effect any of the well known mechanism designed for the production of top machine patterns will be found useful, such mechanism usually comprising two bars having covering needles and being adapted to be shifted longitudinally and independent of each other.

What I desire to secure by Letters Patent of the United States, as my invention, is:

1. A knitted fabric comprising a closely woven body of straight loops and having pairs of adjacent loops inclined relatively to the straight loops and crossing, said crossed loops providing a pattern projecting from the closely woven body formed by the straight loops.

2. In the manufacture of frame work knitted fancy fabrics, the method of producing figures, consisting in laterally shifting within a course the loops not contributing to the formation of the figure to empty needle-hooks disposed between adjacent portions of the figure.

3. In the manufacture of frame work knitted fancy fabrics, the method of pro-

ducing figures, consisting in laterally shifting within a course the loops not contributing to the formation of the design to empty needle-hooks disposed between adjacent portions of the figure, and one of the figure forming loops so that the same crosses the associated loop not shifted.

4. In the manufacture of frame work knitted fancy fabrics, the method of producing figures, consisting in allotting loops to the formation of the figure, and shifting the remaining loops to needle hooks disposed between adjacent portions of the figure and within the same course, said needle hooks becoming temporarily empty during the action of transference of said loops.

5. In the manufacture of frame work knitted fabrics, the method of producing figures, consisting in allotting loops to the formation of the figure, shifting the remaining loops to needle hooks disposed between adjacent portions of the design and within the same course, said needle hooks becoming temporarily empty during the action of transference of said loops, and shifting one of said design forming loops so that the same crosses the associated design forming loop.

6. In the manufacture of frame work knitted fabrics, the method of producing figures, consisting in allotting groups of loops to the formation of the figure, shifting the remaining loops to needle hooks disposed between adjacent portions of the figure and within the same course, said needle hooks becoming temporarily empty during the action of transference of said loops, and shifting one part of a group of said figure forming loops so that the same crosses the other part of the same group of said figure forming loops.

In testimony whereof I have signed my name.

EMIL ALBERT DRECHSEL.
